UNITED STATES PATENT AND TRADEMARK OFFICE
CERTIFICATE OF CORRECTION

PATENT NO. : D859,209 S
APPLICATION NO. : 35/505365
DATED : September 10, 2019
INVENTOR(S) : MacAndrew et al.

Page 1 of 3

It is certified that error appears in the above-identified patent and that said Letters Patent is hereby corrected as shown below:

On the Title Page

Below the Description, “1 Claim, 21 Drawings” should read --1 Claim, 7 Drawings-- as shown on the attached title page

In the Description, delete:

“1.1 : Perspective

1.2 : Back

1.3 : Top

1.4 : Perspective

1.5 : Front

1.6 : Left

1.7 : Top

2.1 : Perspective

2.2 : Back

2.3 : Top

2.4 : Perspective

2.5 : Front

2.6 : Left

2.7 : Top”

In the Drawings

On Sheet 1 of 21, delete Figure 1.1

On Sheet 2 of 21, delete Figure 1.2

On Sheet 3 of 21, delete Figure 1.3

Signed and Sealed this
Twenty-first Day of April, 2020

Andrei Iancu
Director of the United States Patent and Trademark Office

CERTIFICATE OF CORRECTION (continued)
U.S. Pat. No. D859,209 S

Page 2 of 3

On Sheet 4 of 21, delete Figure 1.4

On Sheet 5 of 21, delete Figure 1.5

On Sheet 6 of 21, delete Figure 1.6

On Sheet 7 of 21, delete Figure 1.7

On Sheet 8 of 21, delete Figure 2.1

On Sheet 9 of 21, delete Figure 2.2

On Sheet 10 of 21, delete Figure 2.3

On Sheet 11 of 21, delete Figure 2.4

On Sheet 12 of 21, delete Figure 2.5

On Sheet 13 of 21, delete Figure 2.6

On Sheet 14 of 21, delete Figure 2.7
